UNITED STATES PATENT OFFICE.

FRANCIS H. BROWN, OF RIDLEY PARK, PENNSYLVANIA.

METHOD FOR CONTROLLING COMBUSTION.

1,098,935.

Specification of Letters Patent.

Patented June 2, 1914

Application filed November 28, 1911. Serial No. 662,814.

To all whom it may concern:

Be it known that I, FRANCIS H. BROWN, a citizen of the United States, residing at Ridley Park, Delaware county, State of Pennsylvania, have invented a new and useful Method for Controlling Combustion, of which the following is a specification.

The object of my present invention is to provide a new method of controlling combustion wherein the rate of combustion in one or more furnaces will be automatically maintained uniform in all furnaces regardless of the thickness of the bed of fuel, that is to say, the rate of combustion will be maintained the same on a thick fire as on a thin fire and the rate of combustion on all the fires will simultaneously and automatically vary in accordance with the variations in the demands on the furnaces or the demands for steam and the entire operation of controlling combustion is rendered automatic, thereby enabling me to entirely eliminate the manual control or interference with the draft for combustion, its introduction to the ash pit of each furnace, the exit of the products of combustion from the furnace, and the supply of fuel to the furnace in cases where mechanical stoking is employed.

In plans as heretofore employed for this purpose the efficiency of the automatic control has been greatly reduced and in some cases eliminated, owing to the fact that the draft for combustion was capable of being more or less interfered with by the attendant or fireman, the result of which was that such attendant or fireman would use at times an excessive amount of draft or the reverse regardless of the thickness of the fire so that the conditions of control could not be maintained uniform and therefore satisfactory results were only obtained when the thickness of the bed of fuel, the load requirements and the draft conditions were coincidently in a certain relation.

In my present invention the attendant or fireman does not in any way interfere with the admission of the draft supply to the ash pit for combustion, or the supply of fuel to the furnace, or the discharge of the products of combustion from the furnace.

In my present invention, I maintain a predetermined condition of pressure above

the bed of fuel under all rates of combustion and a varying draft pressure in the ash pit, said ash pit pressure varying in accordance 55 with the stack draft, the thickness of the bed of fuel and the load requirements, so that the rate of combustion will be the same on a thick as on a thin fire, all of said control varying simultaneously and automatically 60 according to the demands for steam and in such a manner as to maintain a uniform steam pressure in the boilers and obtain a very high furnace and boiler efficiency.

My invention further consists of a novel 65 system of controlling combustion wherein the draft producing mechanism is operated at a constant speed, producing a fixed draft pressure in a main draft discharge conduit, and the chimney draft is varied according 70 to variations in the steam pressure, while the admission of air to the main draft conduit, the operation of the stoker and the means for controlling the exit of the products of combustion from the furnace are all 75 automatically controlled by variations in the steam pressure, while the admission of draft for combustion beneath the bed of fuel in each furnace is individually and automatically controlled by variations of pressure 80 within the furnace.

In the accompanying drawings I have shown a sectional elevation of one type of furnace in conjunction with which my novel method may be employed with very advantageous results, although it is to be understood that the same is adapted to be employed with any desired type of furnace and is not limited to use with the type herein shown for the purpose of illustration. 90

Figure 1 is a sectional elevation of a furnace showing a device embodying my invention in operative relation with respect thereto. Fig. 2 is an end elevation of a portion of Fig. 1. Fig. 3 is a sectional elevation of another embodiment of my invention, showing more particularly the electrical control of the fuel feeding means. Fig. 4 represents a sectional elevation of the steam pressure actuated regulator seen in 100 Fig. 1. Fig. 5 represents an elevation partly in section of a portion of Fig. 4. Fig. 6 represents a side elevation of a portion of Fig. 4. Fig. 7 represents a sectional view of

a portion of Fig. 4. Fig. 8 represents a side elevation of a portion of Fig. 4. Figs. 9, 10 and 11 represent, respectively, sectional views of portions of Fig. 4. Fig. 12 represents a side elevation showing one manner of connecting the engine to the stoker grate. Fig. 13 represents a side elevation showing one manner of connecting the electric motor, seen in Fig. 3, to the stoker grate. Fig. 14 represents a sectional elevation of the furnace pressure actuated regulator seen in Fig. 1. Fig. 15 represents a section on line $x-x$ Fig. 14. Fig. 16 represents a plan view having certain parts removed for clearness of illustration.

Similar numerals of reference indicate corresponding parts in the figures.

Referring to the drawings, 1 designates a furnace of any desired type, which in the present instance is provided with an endless grate 2 beneath which is located the ash pit 3. The ash pit is provided with a wall 4 at one end so that the air in the ash pit will not escape through the ash receiving chamber 5.

6 designates the furnace and combustion chamber above which is located a boiler 7.

8 designates a connecting flue through which the waste products of combustion pass from the furnace to a main flue 45.

9 designates a steam conduit which leads to an automatic boiler pressure actuated regulating mechanism 10 the construction of which will hereinafter be fully set forth. 35 The regulating mechanism 10 is provided with a diaphragm which is actuated by the variations of steam pressure to control a valve mechanism 11 which in turn controls the admission of motive fluid to actuate a motor 12 which latter controls the rocking movement of a lever 13. The lever 13 controls a valve mechanism 14 which latter controls the passage of steam through a conduit 15 which is provided with a suitable valve 16, the steam passing from the valve mechanism 14 to a steam conduit 17 provided with a valve 18 and leading to a motor 19 which controls the operation of a stoker grate 2 of any desired or conventional type with which the hopper 20 communicates, and since any desired type of stoker mechanism may be employed, I have deemed it unnecessary in the present instance to illustrate and describe in detail the construction and operation of such a construction.

20 designates a hopper which discharges on to the stoker grate 2. This steam conduit 15 has a branch conduit 21 leading 60 therefrom which is provided with a valve 22, said branch conduit 21 leading to an engine 23 driving a draft producing mechanism 24, such as for example, a fan, which is adapted to operate at a constant speed.

The draft producing mechanism 24 is provided with a draft discharge conduit 25 which leads to a main draft conduit 26 extending in front of a battery of boilers and having branch conduits 27, each of which leads to one of the ash pits 3, as will be apparent to those skilled in this art.

28 designates dampers in the flues 8 leading to the main flue 45, and operatively connected with a cable 29, and provided with counterbalances 30. The cable 29 passes 75 over sheaths 32 which are connected with each other by cables 33 so that the cable 29 will move the dampers 28 in one direction, and the counterbalances 30 will move the same in the opposite direction. The 80 cable 29 passes over pulleys 31 and is connected with the pivoted lever 13 whereby the regulating mechanism 10 will automatically control the movement of the dampers 28 in accordance with the variation of steam 85 pressure.

36 designates a furnace pressure actuated regulator of any desired or conventional type, the construction of which will be hereinafter fully set forth, it being understood 90 that it is only necessary that a pressure regulator be employed which communicates with the interior of the furnace so that a variation of pressure within the furnace will operate a cable 37 which latter passes over 95 rollers 38 and is operatively connected with a damper 39 located in a branch 27 and provided with a counterbalance 40.

The damper 41 in the connecting flue 8 is provided with a cable 42 passing over 100 pulleys 43 to the front of the boiler, thus providing manual means to start or stop the boiler when desired by opening or closing the damper. Each damper 41 is provided with a counterweight 44. Particular attention is directed to the fact that the damper 41 is never employed to regulate the combustion but is only used when it is desired to place one boiler in operation or out of operation, it being apparent that 110 when the damper 41 is closed the damper 39 will also be closed.

In operations of this character as heretofore carried out, it has been found impracticable to obtain a uniform rate of combustion in each furnace owing to the difference in thickness of the different fires and the constantly changing thickness of all fires and the inattention of the fireman to properly adjust a hand damper admitting and 120 controlling the draft to meet the requirements of the changing conditions of the fire.

In my present invention, I employ means for varying the draft below the bed of fuel 125 individually to each furnace in accordance with the opening of the damper 28 or in accordance with any change in the pressure

within the furnace and the thickness of each fire, so that a thick fire offering more resistance to the draft will get a greater draft pressure and volume in the ash pit while the draft on the thin fire would be correspondingly cut down.

The construction and operation of the regulator 10 will now be described, special attention being directed to Figs. 4 to 13 inclusive. The steam passing from the boiler 7 through the conduit 9, passes into the chamber 50, above a diaphragm which is constructed and operates in the manner now to be fully set forth.

51 designates an upper diaphragm, and 52 designates a lower diaphragm, between which is located a central spacing block 53.

54 designates spacing rings, any desired number of which may be employed and 20 which form a flexible joint near the outer periphery of the diaphragms 51 and 52.

55 designates a spacing annulus between the diaphragms 51 and 52, the parts being secured in assembled condition by means of 25 fastening device 56, which pass through the diaphragms 51 and 52, the annulus 55, and the two parts of the casing of the regulator 10. The central spacing block 53 is apertured as indicated at 57, in order that a bar 30 58 may be pivoted therein on the pivot pins 59 and 60, as will be best understood by reference to Fig. 16. This bar 58 has secured thereto an arm 61, mounted in an aperture 62 which extends through the central spacing block 53, the rings 54 and the spacing annulus 55, and is pivotally supported on the pins 63 and 64.

65 designates an aperture extending through the spacing block 53, the rings 54 and the annulus 55, as best seen in Fig. 12, in order that an arm 66 secured to the bar 58 may freely move therein, so that the movement of the diaphragm may be communicated to mechanism exterior of the diaphragm casing in such a manner as to entirely eliminate the friction which ordinarily takes place in devices of this general character. The diaphragm construction herein described, forms the chamber 50 on one side 45 of the diaphragm and a chamber 67 on the opposite side thereof, and the standard of pressure which is desired in the chamber 67 is provided by the proper actuation of the valve controlled conduit 68 which communicates with both of said chambers, it being seen that the liquid in the chamber 67 seals the lower open end of an inverted container 69, thereby forming an air cushion 70 within such container, the air cushion being varied as desired by controlling the fluid passing through the valve controlled conduit 68 until the desired standard of pressure is provided on one side of the diaphragm. The arm 66 has connected therewith an arm 71,

which latter, by means of an adjustable connection 72, is connected with a bell crank lever 73 pivotally supported at 74, and provided with an adjustable counterbalance 75. The bell crank lever 73 is provided with a worm 77, which meshes with a ratchet arm 78, pivoted at 79, to the lever 73 and provided with a bar or guide 80 the inclination of which may be varied as desired by actuating the worm 77, whereby the amount of travel imparted to the shoe 81 may be varied 75 as desired. This shoe 81 is connected with a lever 82 fulcrumed at 83 to a bracket 84, carried by a piston rod 85. The bracket 84 is prevented from rotating by means of the rod 86 passing through an aperture 87, in 80 the casing 12. The lever 82 is connected with a valve stem 88, provided with a plurality of heads 89 and 90 and a reduced neck 91. The valve heads 89 and 90 coöperate with ports in a valve bushing 92 which is 85 secured in the piston 93 having the enlarged heads 94 and 95 and a reduced neck 96. The casing 12 is provided with a port 97, see Fig. 4, whereby motive fluid passes into the chamber of the casing 12 between the heads 90 94 and 95, and the flow of the motive fluid to actuate the piston 93 is as follows:—The motive fluid passes from the internal chamber of the casing through a port 98, and through the port 99 in the valve bushing 92 95 into the chamber 100. Assuming that the valve stem 88 is moved downwardly the motive fluid will pass from the ports 99, around the reduced neck 91 of the valve, and since the valve head 90 has uncovered the 100 ports 101 the motive fluid will pass through the passages 102, beneath the piston 93, and cause the same to move upwardly, it being understood that assuming that the diaphragm does not move the movement of the 105 piston 93 will cause the valve head 90 to register with the port 101 on a predetermined upward movement of the piston 93. On such upward movement of the piston 93, and when the valve heads 89 and 90 have 110 changed their position to reverse the movement of the piston 93 the motive fluid in the chamber 103 will exhaust through the passages 102 the ports 104, and the port 105 in the lower end of the valve bushing 92, and 115 thence through the hollow piston stem 106, the passage 107 in the brackets 108, and thence through the conduit 109 to a desired point of utilization or discharge. If the valve heads 89 and 90 move upwardly, the 120 valve head 90 will close the ports 101, and the valve head 89 will open the ports 110 and permit live motive fluid to pass through the passages 111, into the chamber 112, and thus cause the piston 93 to move downwardly. The motive fluid in the chamber 112 exhausts therefrom through the passages 111, ports 113, and port 114, into the

chamber 115 of the piston 93, and therefrom through the passage 116 into the chamber 117 which communicates with the conduit 106.

5 It will thus be seen that in accordance with the movement of the diaphragm, a travel in the proper direction is imparted to the piston 93, and since the bracket 108 is connected therewith the pin 118, which engages the slot 119 of the lever 13, will cause said lever to be rocked on its fulcrum 120 and through the medium of the slot 121 and the pin 122, imparting a travel to the valve rod 123. The valve rod 123 has connected therewith a cup shaped valve 124, having ports 125 at its closed end, in order to balance the same. The valve mechanism 14 is provided with an inlet port 126, with which the steam conduit 15 communicates, and 10 with a discharge port 127, with which the conduit 17 communicates. The inlet 126 communicates with an annular chamber 128, having ports 129 in its side with which latter are adapted to register ports 130, in the 15 valve 124.

It will be understood that the valve 124 is longitudinally moved by the actuation of the lever 13 and I provide novel means for causing a partial rotation of the valve during such longitudinal movement. The valve rod 123 has adjustably connected therewith a shoe 131 which engages a guide 132, carried by a bracket 133, which is pivoted at 134 to the arm 135 of a split sleeve 136 provided with a screw 137, whereby the same may be fastened to the casing of the valve mechanism 14. The bracket 136 has mounted thereon a worm 138 which meshes with a rack 139 on the bracket 133 whereby the inclination of the guide 132 may be varied as desired, thereby varying the amount of partial rotation of the valve 124, and thus the amount of steam passing from the conduit 15 to the conduit 17 so that the motor 19 20 controlling the stoker, illustrated as comprising the traveling grate 2 is automatically controlled in accordance with variations of speed pressure.

The construction and operation of the 25 pressure regulator 36 will be clearly apparent from Figs. 1, 14 and 15. The casing 140 has an apertured extension 141 communicating with the combustion chamber 6 of the furnace whereby the pressure in the furnace is exerted against a diaphragm 142 having its outer periphery fixed as at 143, provided with a plate 144 to which is adjustably connected one end of the lever 145, by means of a set screw 146 which is in 30 swiveled connection with the plate 144. The lever 145 is fulcrumed at 147 and provided with an arm 148, to which is pivoted an inverted container 149 having a removable plug 150. The open end of the container

149 is liquid sealed to form an air chamber 65 151. The lever 145 has an adjustable connection 152 connected with an arm 153, which controls the valve mechanism 154 to which live motive fluid is conducted through the pipe 155.

70 156 and 157 designate conduits communicating with the chamber 158 of a motor 159 on opposite sides of a piston 160 provided with a stem 161, to which is connected the cable 37, whereby the valves or dampers 39, 75 of each individual furnace are automatically controlled with variations of pressure within its respective furnace. The exhaust in the valve mechanism 154 passes through a discharge conduit 162 into the container 163, 80 in order to maintain a constant level therein, said container being provided with a discharge conduit 164.

85 165 designates a valve controlled conduit adapted to communicate with a source of fluid supply, whereby the volume and pressure of the cushion 151 may be varied as desired.

90 The operation and purpose of my novel method will now be readily apparent to those skilled in the art to which this invention appertains and is as follows:—As the steam pressure begins to lower, the regulating mechanism 10, which is controlled by variations of steam pressure, will cause the 95 lever 13 to be rocked on its fulcrum thereby causing the cable 29 to open the dampers 28. As the pressure within the furnace varies the pressure regulator 36 will be actuated thereby causing the cable 37 to actuate the 100 damper 39 and thus permit the air for combustion to pass into the ash pit 3 beneath the bed of fuel on the endless grate 2.

105 Particular attention is directed to the fact that in my present invention I eliminate entirely the manual control of the draft for combustion and maintain the same rate of combustion on all fires alike regardless of the differing thickness of the various fires and the entire operation is automatic. The 110 stack damper 28 and the stoker (where mechanical stoking is employed) are automatically controlled by variations in steam pressure and the admission of air to each ash pit is automatically controlled by the 115 variations of pressure within the furnace above the bed of fuel. As the bed of fuel increases in thickness it is necessary to increase the draft pressure to maintain the same rate of combustion and in order to 120 maintain a uniform condition of pressure above the bed of fuel as the pressure in the combustion chamber decreases, the regulator 36 will be actuated in a direction to increase the draft pressure below the bed of fuel and thereby increase the combustion. It is also 125 necessary to vary the draft pressure below the bed of fuel as the damper in the main

flue is moved in the direction of either opening or closing, due to the rise or fall of the steam pressure, and this is very accurately and reliably done by the employment of my 5 novel controlling devices. Under these conditions just the amount of air necessary to support combustion to meet the demands for steam will be supplied and no more, and each fire will be made to perform its share of the 10 work, the result of which is that a constantly high furnace efficiency is obtained which will not be interfered with by the fireman or engineer attempting to manually control the draft.

15 The steam pressure actuated regulator 10 is described and broadly claimed in a co-pending application Serial No. 583,176, filed Sept. 22, 1910, while the furnace pressure actuated regulator is described and 20 broadly claimed in a co-pending application Serial #664,613, filed Dec. 8, 1911.

In the broad and generic scope of my invention it is immaterial whether the speed of the draft producing mechanism is automatically controlled by the variations of 25 steam pressure or driven at a constant speed by an electric or other motor, as indicated at 46 in Fig. 3, it being understood that the damper 39 would operate in the manner 30 above described in the operation, and it is also immaterial whether the stoker is controlled by variation of steam pressure controlling the engine driving the stoker as described in the operation or controlled by 35 variations of steam pressure through the lever 13, as seen in Fig. 3 wherein the lever 13 is adjustably connected with a lever 47 of a rheostat 48 controlling the speed of the electric motor 49 which drives the stoker 40 illustrated herein as a traveling grate 2. Both manners of operating the fuel feeding means and the draft producing mechanism have given very advantageous results in practice, and it is to be understood that both 45 are within the spirit and scope of my invention.

It will be apparent that in accordance with my present invention, I control the draft pressure anterior to the burning fuel 50 by first automatically varying the pressure posterior to the burning point of the fuel, in accordance with variations of load on the furnace, and I then utilize the variations of pressure thus produced to automatically 55 vary the introduction of air anterior to the burning point of the burning fuel, the result of which is that one is enabled to maintain a substantially constant difference of pressure between the pressure anterior to 60 and the pressure posterior to such burning point, and the standard of such difference of pressure may be varied by adjusting the furnace pressure actuated regulator 36.

Having thus described my invention, what

I claim as new and desire to secure by Letters Patent, is:—

1. The method of controlling combustion in furnaces, which consists in varying the pressure above the fires to vary the rate of combustion on all the fires, simultaneously 70 and proportionately to variations of load on the furnaces, and varying the draft for combustion to maintain an equal rate of combustion on all the fires which is substantially constant for varying thicknesses of 75 the beds of fuel.

2. The method of controlling combustion in furnaces, which consists in varying the pressure above the fires to vary the rate of combustion on all the fires, simultaneously 80 and proportionately to variations of load on the furnaces, and automatically varying the draft for combustion for each individual fire in accordance with the thickness of its bed of fuel to maintain an equal rate of 85 combustion on all the fires.

3. The method of controlling combustion in furnaces, which consists in varying the rate of combustion on all the fires simultaneously and proportionately to variations 90 of steam pressure to thereby vary the pressure in each individual furnace, and utilizing the variations in pressure in each individual furnace to vary the draft for combustion in accordance with the thickness 95 of its bed of fuel and thus maintain an equal rate of combustion on all the fires.

4. The method of controlling combustion in furnaces, which consists first in varying the rate of combustion on all the fires, simultaneously 100 and proportionately to variations of load on the furnaces to vary the condition of pressure within each furnace, and then automatically varying by means of such variations in pressure, the draft for 105 combustion for each individual fire in accordance with the thickness of its bed of fuel to maintain an equal rate of combustion on all the fires.

5. The method of controlling combustion 110 in furnaces which consists in varying the pressure above the fires to vary the rate of combustion on all the fires simultaneously and proportionately to variations of load on the furnaces, varying the draft for combustion for each individual fire in accordance with the thickness of its bed of fuel to maintain an equal rate of combustion on all the fires, and automatically varying the fuel feed in accordance with the variation of 115 load on the furnace.

6. The method of controlling combustion in furnaces, which consists in varying the pressure above the fires, to vary the rate of combustion on all the fires proportionately 125 to variations of steam pressure in the furnaces, simultaneously therewith controlling the fuel feed in accordance with variations

of steam pressure, and automatically controlling the introduction of draft beneath the bed of fuel of each individual furnace in accordance with the variations of pressure within each individual furnace.

7. The method of controlling combustion in furnaces, which consists in automatically varying the pressure above the fires to vary the rate of combustion on all the fires in accordance with variations of steam pressure, feeding air to the ash pit of each furnace, automatically controlling the introduction of air into each ash pit in accordance with the variations of pressure within its respective furnace, and in accordance with the thickness of the bed of fuel of each individual furnace to maintain an equal rate of combustion on all the fires, feeding fuel to the fires, and automatically controlling the fuel feeding means simultaneously and proportionately to variations of load on the furnaces.

8. The method of controlling combustion in a furnace, which consists in first varying the pressure within the furnace in accordance with the variations in steam pressure, and then utilizing the variations in pressure thus formed within the furnace to automatically control the admission of draft beneath the bed of fuel.

9. The method of controlling combustion, which consists in feeding fuel to the grate, feeding air to the ash pit, automatically varying the pressure within the furnace by variations in steam pressure, automatically controlling the fuel feeding means by variations of steam pressure, and automatically controlling the introduction of air to the ash pit by the variations of pressure within the furnace thus produced.

10. The method of controlling combustion, which consists in automatically controlling the exit of the products of combustion from the furnace by variations of steam pressure to first vary the pressure within the furnace, second automatically varying the draft beneath the bed of fuel in accordance with the thickness of the bed of fuel and the condition of pressure within the furnace above the bed of fuel, automatically controlling the fuel feed by variation of the steam pressure, and actuating the draft producing means at a constant speed.

11. The method of controlling draft pressure in the ash-pit of a furnace, which consists in first automatically varying the pressure above the bed of fuel in accordance with variations of load on the furnace, and in utilizing the variations of pressure thus produced, to automatically vary the introduction of air into the ash-pit, and thereby maintain a substantially constant difference of pressure between the pressure above the bed of fuel and the pressure in said ash-pit.

12. The method of controlling the draft pressure in the ash-pit of a furnace, which consists in first varying the pressure in the combustion chamber in accordance with variations in load on the furnace, and then varying the draft pressure in the ash-pit in accordance with such variations of pressure in the combustion chamber and the variations in thickness of the bed of fuel, and thereby maintain a substantially constant difference of pressure between the pressure in the combustion chamber and the pressure in the ash-pit.

13. The method of controlling combustion in furnaces, which consists in first changing the stack or induced draft on a plurality of furnaces to vary the rate of combustion on all the fires simultaneously and proportionately to variations of load on the furnaces, thereby changing the condition of pressure above the beds of fuel, then utilizing such change of furnace pressure to vary the introduction of draft for combustion on each individual furnace according to the resistance offered such draft by the thickness of its bed of fuel to thereby maintain an equal rate of combustion of all the fires.

14. The method of controlling combustion, which consists first, in automatically varying the conditions within the furnace in accordance with the variations of load on such furnace, and then utilizing the variations of conditions within the furnace to vary the draft for combustion in accordance with the resistance offered such draft.

15. The method of controlling combustion in furnaces, which consists, first, in varying the conditions within each individual furnace in accordance with the variations of load on each furnace, and then utilizing the variations in condition in each individual furnace to automatically control the introduction of draft for combustion for such furnace in accordance with the variations in the thickness of its bed of fuel.

16. The method of controlling combustion which consists first, in automatically varying the conditions in the furnace in accordance with variations in load on the furnace, and then varying the draft for combustion in accordance with such variations and the varying resistance offered the draft for combustion introduced beneath the bed of fuel.

17. The method of controlling the draft pressure anterior to the burning point of the burning fuel in accordance with variations in load on the furnace, which consists in first automatically varying the pressure posterior to the burning point of the fuel, and then utilizing the variations of pressure thus produced to automatically and correspondingly vary the introduction of air anterior to the burning point of the fuel and thereby maintain a substantially constant

difference of pressure between the pressure anterior to and the pressure posterior to said burning point of the fuel.

18. The method of controlling combustion, which consists in automatically varying the conditions within the furnace in accordance with variations in load on the furnace, and utilizing the varying conditions within the furnace to control introduction of draft

beneath the bed of fuel and thereby maintain a uniform difference between the pressure of gases within the furnace above the bed of fuel and the draft pressure beneath the bed of fuel. 10
